CHESS GAME RECORDER

Arthur W. Fey, Hazleton, Pa.

Application December 7, 1945, Serial No. 633,417

15 Claims. (Cl. 234—1.5)

1

This invention relates to game-recording devices, and more particularly to automatic recording apparatus associated with a playing board upon which chess, checkers, or similar games may be played, which games utilize marked squares or spaces upon which the game pieces are moved.

Students of the game of chess frequently find it beneficial to replay and analyze games played by experts, and to study games played by themselves, to find fallacies in their play and to improve their technique. To make this possible, it is necessary that a record of each play be kept. This is not only a tedious task when set down by hand but there is always the possibility of error.

The object of the present invention is to provide automatic apparatus to record chess games or the like as they are played to provide an exact record of each play of the game upon its completion.

Another object of the invention is to provide such apparatus which is controlled by the players, without undue effort on their part, simply by exerting slight pressure upon the game piece to be moved, before and after the move.

A further object of the invention is to provide such apparatus which, when its operation is initiated, goes through its entire cycle of operation and resets itself to be in readiness for another cycle.

A still further object of the invention is to provide such apparatus operating upon a system characterized by the employment of certain characters indicative of longitudinal rows on the playing board, and other characters designating transverse rows, whereby various combinations of the two will give a designation for each square upon the board, and the number of type bars necessary is reduced materially.

Other objects of the invention will become apparent from the following description taken in conjunction with the drawings which accompany and form a part of this specification, and throughout the several figures of which like numerals refer to identical parts.

In the drawings:

Fig. 1 is a perspective view of a game board in which the apparatus is installed;

Fig. 2 is a horizontal section taken on the line 2—2 of Fig. 3;

Fig. 3 is a vertical transverse section taken on the line 3—3 of Fig. 2;

Fig. 4 is a longitudinal section taken on the line 4—4 of Fig. 2;

Fig. 5 is a horizontal sectional view taken on the line 5—5 of Fig. 3 looking at the underside of the playing surface;

2

Fig. 6 is a view taken on the line 6—6 of Fig. 3 looking downward;

Fig. 7 is a partial plan view showing some of the solenoids shown in Fig. 2 and the manner in which a movable type carriage coacts therewith;

Fig. 8 is a diagrammatic view showing the electrical circuits controlling the apparatus.

Referring in detail to the drawings, a playing surface 10, suitably marked off for the playing of chess or similar games, forms the top of a rectangular box-like structure 11 of sufficient depth to house the recording apparatus of the present invention.

15 The playing surface 10 is marked off in the usual fashion defining sixty-four squares, forming eight rows longitudinally and eight rows transversely. For recording purposes, the longitudinal rows are designated by letters, and the transverse rows by numbers. For purposes of illustration, these letters and numbers are shown on Fig. 1, the letters A, B, C, D, E, F, G, H designating the longitudinal rows, and the numbers 1, 2, 3, 4, 5, 6, 7, 8 designating the transverse rows. Thus every square on the board has its individual designation comprising a letter and a number, as A—1, C—6, E—4, etc. By this method it is possible to record the play in a chess game by recording the square upon which the piece is placed after the move. The 20 game can be replayed from the record by a sequential movement of the game pieces from the squares indicated to the next designated square in the order of their appearance on the recorded sheet.

25 35 To bring this about, the playing surface 10 is formed of some flexible material and is provided with a plurality of metallic contact members 12, one affixed to the underside of each of the playing squares. Positioned below the playing surface, 40 spaced therefrom a slight distance, is a rigid horizontal partition 13 supported along its four edges upon strips 14 fixed to the inside walls of the housing 11. Partition 13 has a plurality of metallic contacts 15 secured upon its upper face, the contacts 15 being similar and equal in number to the contacts 12 carried by the flexible playing surface. The contacts 15 are so positioned that each one lies directly beneath its companion contact 12. When a player makes a move on the 45 board, a slight pressure on the game piece will close the contacts 12 and 15 beneath the square upon which the piece is resting, closing a circuit, to be described hereinafter, setting the recording apparatus into operation. This will indicate the 50 55 piece being moved. The player will then move

the piece and exert a slight pressure upon the square to which the piece is moved to record the movement of the playing piece.

The closing of contacts 12 and 15 will energize one coil in each of two banks of solenoids 16 and 17, the bank 16 consisting of eight coils 18 representing the numbered rows of squares on the playing board, and the bank 17 consisting of eight coils 19 representing the lettered rows. Due to certain electrical connections, the closing of the contacts 12 and 15 of a particular square will cause energization of a coil 18 corresponding to the numbered row in which the square belongs, and energization of a coil 19 corresponding to the lettered row of that particular square.

The energization of a coil will cause a pop-up rod 20, which forms the pole-piece of the solenoid, to rise. It will be noted that the solenoid banks 16 and 17 are arranged at an angle. This is to place the solenoid pop-up rods 20 at progressively greater distances from the leading edges of type-carriages 23 and 24.

After the pop-ups rise coils 25 and 26 are energized which draw the type-carriages forward until they strike the lifted pop-ups 20 in the solenoid banks 16 and 17 respectively. Due to the fact that the carriages are moved by independent coils the two carriages may be moved different distances. Thus if the left-hand coil 18 in bank 16 is energized, which coil is closest to carriage 23, and the left-hand coil 19 of bank 17 is energized, which is farthest from carriage 24, carriage 23 will move its shortest distance and carriage 24 will move its greatest distance.

The type-carriages comprise a substantially U-shaped frame 27 (see Fig. 2) to which is secured a bumper strip 28. The carriages are mounted upon rods 29 which are slideable in bearings 30 fixed to a base plate 31 secured within the housing 11. The open end of the U-frame is bridged by a shaft 32 upon which type bars 33 are pivotally supported. The inner ends of the type bars carry the type 34, the eight type bars of carriage 23 bearing the numerals 1 to 8 inclusive, and the eight type bars of carriage 24 bearing the letters A to H inclusive. The positioning of the bars will agree with the positioning of the coils in the solenoid banks. In other words, the type bar on carriage 23 which is closest to the solenoid bank will bear the number of the playing surface row which controls the left-hand solenoid of bank 16. The next type bar corresponds to the row controlling the next solenoid, etc. The converse is true in respect to the carriage 24. The type bar closest to bank 17 bears the letter of the playing board row which controls the right-hand coil of solenoid bank 17, etc. The angular position of the solenoid banks 16 and 17 is such that the distance between parallel planes passing through the centers of the coils, the planes being parallel to the type-carriage bumpers, is equal to the distance between centers of adjacent type bars on the type carriages.

As soon as the carriages have moved forward, a paper record strip 35 is drawn from a roll 36 and advanced by mechanism to be described later.

Moving the carriages forward brings the type bars under a type-striker 37. The type-striker is pivotally attached to the lower end of a solenoid pole-piece 38. Movable within the coil 39 and extending beyond the opposite end of the coil to carry a coiled spring 40 which normally holds the pole-piece 38 and striker 37 in raised position. The upper end of the pole-piece 38 is provided

with an enlarged head to serve as an abutment for the spring. Energization of coil 39 moves the striker 37 downward, striking the type bars positioned beneath it, causing an impression of both bars, viz. A-1, E-6, etc. to be made upon the paper strip 35 held in a guide trough 41 below the type bars. The pivotal connection of the striker permits a floating action, ensuring even pressure on both type bars. A carbon strip 42 is placed above the paper to be struck by the type bars to make the impression upon the paper, and the carbon is advanced with the paper.

The paper strip is advanced by means of a coil 43 which has a pole-piece 44, to the outer end of which a resilient member 45 is pivotally connected. The member 45 has a coiled spring 46 attached to its opposite end. Between its ends the member 45 carries a dog 47 for engagement with a ratchet wheel 48 fixed upon the end of a shaft of one of two paper feed-rolls 49. A spring pawl 50 prevents reverse rotation of the ratchet wheel. When coil 43 is energized, the pole-piece 44 is drawn in, causing the resilient member 45 to rotate the ratchet wheel 48 by means of the dog 47, thus rotating the feed-rolls 49 and advancing the paper strip. Spring 46 returns the parts to a position of rest when the coil is de-energized.

When the above operations are completed, coils 51 and 52 return the carriages to their positions of rest.

Having described the structural elements of the recording device, attention is now directed to Fig. 8 and the electric circuits which connect and control the various elements to cause a step-by-step operation through a complete cycle.

When a game piece is pressed upon a particular square upon the playing surface, a contact 12 is pressed against a contact 15 to close a circuit to a coil 18 in bank 16 and a coil 19 in bank 17. As shown in Fig. 5, the contacts 12 attached to the underside of the playing surface are connected serially in longitudinal rows so that all contacts in that row are on a common line. This gives eight lines, each running to one of the coils 19 in bank 17. Whenever a game piece is pressed upon any square in one particular row the same coil 19 is energized, as all squares in that row have the same letter. As shown in Fig. 6, the contacts 15 are connected serially in transverse rows so that all contacts in each transverse row are in a common line. This gives eight lines, each running to one of the coils 18 in bank 16. Whenever any square in one particular transverse row is pressed the same coil 18 is energized as all squares in that row have the same number. So a letter coil and number coil are energized each time a square is pressed. For purposes of simplicity only two coils are shown in Fig. 8 in each of the banks 16 and 17, and only two contacts in each of two longitudinal and two transverse rows are shown.

The circuit set up when pressure is applied to a square, begins at a grounded source of power 53 and follows wire 54 to a coil 19 in bank 17 (the particular coil 19 depending upon the square pressed on the playing board) through wire 55 to closed contacts 12, 15, wire 56 to a coil 18 in bank 16, wire 57 to a pilot relay 58, the wire 59 to ground. It should be pointed out that all of the coils 18 in bank 16 are wired in series, as are the coils 19 in bank 17.

The energization of pilot relay 58 draws up its armature 60 closing contacts 61, 62, closing a cir-

cuit to a relay 63. The circuit can be traced from a grounded source of power 64, through wire 65 to the coil of relay 63, wire 66, contacts 62, 61, and pilot relay armature 60 to ground. Relay 63 will draw up its armature 67 closing contacts 68, 69 to establish a circuit to a relay 70 through grounded power source 71, wire 72, relay coil 70, wire 73, contacts 69, 68, and relay armature 67 to ground. The energization of relay 70 closes contacts 74, 75 completing a circuit to another relay 76 through grounded source of power 77, wire 78, relay coil 76, wire 79, contacts 75, 74, and relay armature 80 to ground.

Relay 76, upon energization, will draw up its armature 81 closing contacts 82, 83 to prepare a circuit to be described later. Relays 70 and 76 are both double contact relays having the second contact arms 84 and 85 respectively. The three circuit-controlling relays 63, 70, and 76 are of the well known "slow-release" type, which relays are characterized by the fact that they will maintain momentarily their armatures in drawn-up position after the coil circuit has been broken. The four relays 58, 63, 70 and 76 are connected to operate sequentially, the energization of the first closing a circuit to the second and so on. If it were not for the slow release feature of relays 63, 70 and 76, the breaking of the circuit to relay 58 would cause instant release of relays 63, 70 and 76. The momentary pause in the release of these relays permits certain operations to take place between the breaking of the circuit to the relay coil and the release of its armature which breaks the circuit to the next relay coil. Such an arrangement is necessary so that the majority of the operations may take place as the relay circuits are being sequentially broken, to ensure the completion of the cycle of operation for the energization of the system is controlled by the pressure applied to the playing piece on the board and will be of varying and indeterminate duration.

When the circuit to relay 70 is made, closing contacts 74, 75, circuits are set up through the carriage-advancing solenoids 25 and 26 to move the carriages forward until they strike the raised pop-ups 20 of the energized coils 18 and 19. The circuit through solenoid 25 begins at the grounded power supply 86, through coil 25, wire 87 to point 88, wire 89, wire 79, contacts 75, 74, and armature 80 to ground. The circuit to coil 26 is similar comprising grounded power source 90, coil 26, wire 91 to point 88, wires 89, 79, contacts 75, 74, and relay armature 80 to ground. The forward movement of the carriages will place the desired type-bars under the type striker.

When pressure upon the playing piece is released, contacts 12 and 15 will separate, breaking the circuit through coils 18 and 19 and the pilot relay 58. The pilot relay armature will drop down separating contacts 61, 62, breaking the circuit to the coil of relay 63. Although the circuit to relay 63 will be broken, the relay, being of the slow release type, will maintain its armature in drawn-up position sufficiently long to ensure the carriages reaching their limit of travel before breaking the circuit to relay 70 which controls the circuits to solenoids 25 and 26.

When relay 63 releases its armature, contacts 92, 93 close completing a circuit to the paper strip advancing coil 43, which circuit comprises grounded power source 94, coil 43, wire 95, relay contacts 96, 97, wire 98, contacts 93', 92, and relay armature 67 to ground. The slow release action of relay 70 will hold contacts 96, 97 closed suffi-

ciently long for the paper advancing operation to be completed.

The subsequent release of relay 70 will break the circuits to solenoids 25 and 26, and the circuit to relay 76. Relay 76 will maintain its armature drawn-up for a short period. The release of relay 70 will cause contacts 99, 100 to close, completing a circuit to type-striker coil 39 causing the striker to strike the type bars positioned thereunder and make an impression on the record strip. This circuit includes grounded power supply 101, coil 39, wire 102, relay armature 81, contacts 83, 82, wire 103, contacts 100, 99, relay armature 80 to ground.

Relay 76 will then release, separating contacts 82, 83 breaking the circuit to the type-striker, and closing contacts 104, 105 establishing circuits to the carriage-return relays 51 and 52. The circuit to coil 52 comprises grounded power source 106, spring switch 107, wire 108, coil 52, wires 109, 110, contacts 104, 105, and relay armature 85 to ground. The circuit to coil 51 comprises grounded power source 111, spring switch 112, wire 113, coil 51, wire 114 to wire 110 where the balance of the circuit is the same as that for coil 52.

As the carriages return to their position of rest, they strike switches 107 and 112 breaking the circuits to the carriage-return coils 52 and 51 respectively. As the carriages are independently operated and the operating circuits independently broken, each carriage will be assured of returning to its full return position.

When the carriages have completed their return movement, a complete cycle of operation has been completed and the circuits are in readiness to repeat the cycle when pressure again is applied to a playing piece upon the board.

Although all of the operation of the device has been described in conjunction with the structure and circuits making up the recorder, it is thought that a brief description of the cycle of operation will set out the various steps so as to be more readily understood. In playing the game, the player will decide which game piece is to be moved and, before moving it from the square upon which it is resting, will press upon the game piece, depressing the flexible playing surface to cause the metallic contacts beneath the playing surface to close, energizing a coil 18 in the bank 16, and a coil 19 in the bank 17. The coil pop-ups will rise, and a pilot relay will be energized, which, in turn, causes three control relays to be energized sequentially. One of the control relays causes the energization of the carriage advancing solenoids which draw the carriages forward until they strike their respective pop-ups, which positions the carriages so that the desired type-bars will be under the type striker. When the pressure is removed from the playing piece upon the board the circuits causing the above operations are broken permitting the various relays to return to positions of rest. Due to the fact that the control relays are of the slow release type and these relays are serially connected so that each relay controls the circuit to the next the relay circuits will be broken slowly permitting certain operations to take place after the release of each. As the relays release, the paper-strip advancing coil will be actuated to move the paper forward one space. The type striker will then operate, making an impression upon the paper. After the impression is made the carriage return coils will be energized to draw back the carriages. As each carriage reaches its position of rest it will open a switch breaking the circuit to its respective return coil.

The apparatus will then be in position to again begin the cycle. When the player has moved the piece to its new position, the cycle will repeat as pressure is applied to the board. Thus two printed impressions will be made for each move in the game so that indication will be given of the piece moved and the position to which it is moved.

While I have in the above described what I believe to be a preferred and practical embodiment of the invention, the precise embodiment shown is for purposes of illustration only and many changes may be made in the structure, all within the scope of the appended claims.

Having thus fully described my invention, I claim:

1. In apparatus for recording a game upon a record strip, a playing surface having spaces marked thereon upon which game pieces are to be moved, type bars having characters which are collectively indicative of the position of playing spaces on the board, means operable by pressure being exerted upon said playing surface to select the type bars which together have characters conforming to the position of the space pressed on the playing surface, and means to cause the selected type bars to make an impression upon the record strip.

2. In apparatus for recording a game upon a record strip, a playing surface having spaces marked thereon upon which game pieces are to be moved, a group of type bars having characters indicative of longitudinal positions on said playing surface, a second group of type bars having characters indicative of transverse positions on said playing surface, means operable by pressure being exerted upon said playing surface to select the type bar from each of said groups indicative of the longitudinal and transverse positions of the space pressed on the playing surface, and means to cause the selected type bars to make an impression upon the record strip.

3. In apparatus for recording a game upon a record strip, a playing surface having spaces marked thereon upon which game pieces are to be moved, type bars having characters indicative of the position of the playing spaces on the board, a type striker over said record strip, and means operable by pressure being exerted upon said playing surface to selectively position under said type striker type bars having characters conforming to the position of the space pressed on said playing surface.

4. In apparatus for recording a game upon a record strip, a playing surface having spaces marked thereon upon which game pieces are to be moved, a group of type bars having characters indicative of longitudinal positions on said playing surface, a second group of type bars having characters indicative of transverse positions on said playing surface, a type striker over said record strip, and means operable by pressure being exerted upon said playing surface to selectively position under said type striker the type bar from each of said groups indicative of the longitudinal and transverse positions of the space pressed on the playing surface.

5. In apparatus for recording a game upon a record strip, a playing surface having spaces marked thereon upon which game pieces are to be moved, a movable type carriage, type bars having characters indicative of the linear position of the playing spaces on said board on said carriage, a type striker over said record strip, and means operable by pressure being exerted on said playing surface to move said type carriage to selectively

position under said type striker the type bar having a character conforming to the linear position of the space pressed on said playing surface.

6. In apparatus for recording a game upon a record strip, a playing surface having spaces marked thereon upon which game pieces are to be moved, a pair of type carriages, a group of type bars on one of said carriages having characters indicative of longitudinal positions on said playing surface, a group of type bars on the other of said carriages having characters indicative of transverse positions on said playing surface, a type striker over said record strip, and means operable by pressure being exerted upon said playing surface to move said type carriages to selectively position under said striker the type bar from each of said groups indicative of the longitudinal and transverse positions of the space pressed upon the playing surface.

7. In apparatus for recording a game upon a record strip, a playing surface having spaces marked thereon upon which game pieces are to be moved, a movable type carriage, type bars having characters indicative of the position of the playing spaces on said board on said carriage, a type striker over said record strip, means to move said carriage, and means operable by pressure being exerted upon said playing surface to limit the movement of said carriage to selectively position under said striker the type bar having a character indicative of the position of the space pressed on the playing surface.

8. In apparatus for recording a game upon a record strip, a playing surface having spaces marked thereon upon which game pieces are to be moved, a pair of type carriages, a group of type bars on one of said carriages having characters indicative of longitudinal positions on said playing surface, a group of type bars on the other of said carriages having characters indicative of transverse positions on said playing surface, a type striker over said record strip, means to move said carriages, and means to limit the movement of said carriages to selectively position under said striker a type bar from each of said carriages indicative of the longitudinal and transverse positions of the space pressed on the playing surface.

9. In game recording apparatus as claimed in claim 8, said carriage moving means comprising separate means to each carriage whereby the carriages may be moved independently of one another.

10. In apparatus for recording a game upon a record strip, a playing surface having spaces marked thereon upon which game pieces are to be moved, a pair of type carriages, a group of type bars on one of said carriages having characters indicative of longitudinal positions on said playing surface, a group of type bars on the other of said carriages having characters indicative of transverse positions on said playing surface, a type striker over said record strip, means to move said carriages independently of one another, a group of limit stops for each carriage the limit stops in each group being spaced from one another at progressively increasing distances from the position of rest of said carriages, and means operable by pressure being exerted upon said playing surface to cause one limit stop of each

group to assume carriage stop position, whereby one type bar of each carriage may be selectively positioned under said type striker, said selected type bars having characters indicative of the longitudinal and transverse positions of the space pressed on the playing surface.

11. In game recording apparatus as claimed in claim 10, the spacing between said limit stops being equal to the spacing between the type bars on said carriages.

12. In apparatus for recording a game upon a record strip, a playing surface having spaces marked thereon upon which game pieces are to be moved, type bars having characters indicative of the position of the playing spaces on the board, means to advance said strip, means to cause selected type bars to make an impression upon the strip, means to control the cycle of operation of said apparatus comprising electric circuits including a pilot relay and control relays, said relays connected for sequential energization when a space upon the playing board is pressed, said control relays being of the slow release type to provide delay between the release of one control relay and the next when pressure is removed from said playing space.

13. In apparatus for recording a game upon a record strip, a yieldable playing surface having spaces marked thereon in longitudinal and transverse rows and upon which game pieces are to be moved, a rigid backing member spaced below said yieldable playing surface, a plurality of spaced parallel contact strips attached to the underside of said playing surface, each contact strip positioned under a row of spaces on said playing surface, a plurality of spaced parallel contact strips on the upper surface of said rigid backing member, the strips of said last-mentioned plurality being positioned at right angles to said first-mentioned plurality, each strip of said last-mentioned plurality being positioned under a row of spaces on said playing surface, whereby one contact of said first-mentioned plurality and one contact of said second plurality will be brought together by pressure upon any one of the spaces of said playing surface, type bars bearing characters indicative of the rows upon said playing surface and means connected in electrical circuit with said contact strips to selectively position type bars bearing characters indicative of the position of the space pressed in printing position.

14. In apparatus for recording a game upon a record strip, a yieldable playing surface having spaces marked thereon in longitudinal and transverse rows and upon which game pieces are to be moved, a rigid backing member spaced below said yieldable playing surface, a plurality of spaced parallel contact strips attached to the underside of said playing surface, each contact strip positioned under a row of spaces on said playing surface, a plurality of spaced parallel contact strips on the upper surface of said rigid backing member, the strips of said last-mentioned plurality being positioned at right angles to said first-mentioned plurality, each strip of said last-mentioned plurality being positioned under a row of spaces on said playing surface, whereby one contact of said first-mentioned plurality and one contact of said second plurality will be brought together by pressure upon any one of the spaces of said playing surface, a pair of type carriages, a group of type bars on one of said carriages hav-

ing characters indicative of longitudinal positions on said playing surface, a group of type bars on the other of said carriages having characters indicative of transverse positions on said playing surface, a type striker over said record strip, and means connected in electrical circuit with said contact strips to move said type carriages when pressure is placed upon one of said spaces to move said type carriages to selectively position under said striker the type bar from each of said groups indicative of the longitudinal and transverse position of the space pressed upon the playing surface.

15. In apparatus for recording a game upon a record strip, a yieldable playing surface having spaces marked thereon in longitudinal and transverse rows and upon which game pieces are to be moved, a rigid backing member spaced below said yieldable playing surface, a plurality of spaced parallel contact strips attached to the underside of said playing surface, each contact strip positioned under a row of spaces on said playing surface, a plurality of spaced parallel contact strips on the upper surface of said rigid backing member, the strips of said last-mentioned plurality being positioned at right angles to said first-mentioned plurality, each strip of said last-mentioned plurality being positioned under a row of spaces on said playing surface, whereby one contact of said first-mentioned plurality and one contact of said second plurality will be brought together by pressure upon any one of the spaces of said playing surface, a pair of type carriages, a group of type bars on one of said carriages having characters indicative of longitudinal positions on said playing surface, a group of type bars on the other of said carriages having characters indicative of transverse positions on said playing surface, a type striker over said record strip, means to move said carriage independently of one another, a group of limit stops for each carriage, the limit stops in each group being spaced from one another at progressively increasing distances from the position of rest of said carriages, and means connected in electrical circuit with said contact strips and operable by pressure being exerted on said playing surface to cause one limit stop of each group to assume carriage stop position, whereby one type bar of each group may be selectively positioned under said type striker, said selective type bars having characters indicative of the longitudinal and transverse position of the space pressed on the playing surface.
